UNITED STATES PATENT OFFICE.

TRACY J. ANSTEY, OF OAKLAND, CALIFORNIA.

REFRIGERATOR-DOOR LATCH.

Application filed June 13, 1921, Serial No. 477,091. Renewed April 17, 1926.

This invention relates to a refrigerator door latch and its object is to provide means whereby the refrigerator door may be maintained under a sufficient pressure to keep it substantially air tight at all times to prevent the loss of cold air and its replacement by hot air within the refrigerator. The latch is intended not for the purpose of securing the door against access but merely to put such a pressure thereon as will prevent it from being loose in its seat while not preventing it from being opened or closed from either side.

Other objects of the invention will appear as the description proceeds.

An embodiment of the invention is shown in the accompanying drawings in which the same reference numeral is applied to the same portion throughout, but I am aware that there may be modifications thereof.

Fig. 1 shows the latch in place on a refrigerator door.

Fig. 2 is an enlarged front elevation of the latch.

Fig. 3 is a sectional view of the latch, a portion thereof being shown in section for purpose of illustration.

Fig. 4 is a side elevation of the latch as it appears when free from the door, and

Fig. 5 is a side elevation of the fixture against which the latch strikes.

The numeral 1 indicates the door jambs. 2 the door which may be hinged thereto in any well known manner. 3 indicates the handle for operating the door. 4 the latch base and 5 the latch fixture against which the latch strikes when the door is closed.

The latch base 4 has an elongated slot formed therein to receive a hollow bolt 6; said bolt being held in place by means of the plate 7 which is secured to the base 4 by means of the four cap screws 8. At the back end of the base 4 there is a post 9 which receives a tube 10; said tube being held in a

fixed position by means of the set screw 11. A heavy spiral spring 12 surrounds the tube 10 and holds the bolt 6 normally in the position shown in Figure 4. When the door is opened a flange 13 on the bolt preventing it from being pushed through the slot in the plate in which it slides. At its other end the bolt 6 has a pivot pin 14 which carries two short links 15 each of which is provided with a hook as indicated at 16. These links

support a pivot pin 17 which carries a roller 18.

The base plate 5 has a post 19 which is of substantially the same width as the space between the two links 15. This post carries a pin 20 which projects on both sides thereof and which engages the two hooks 16 when the door is closed.

In order to insure the two links remaining in the position shown in Figure 4 when the door is opened, one of said links has a hole 21 as indicated at 21 and the bolt 6 has a hole to receive a small spiral spring 22 and ball 23; the both being sufficiently flanged over to prevent the ball from being pushed out of the hole in the bolt 6 more than enough to engage the hole 21 in the link 15.

The operation of the latch is as follows: Assuming the door to be opened and the door moving toward the door jamb, note the position of Figures 4 and 5, the hooks 16 will engage the pin 20 on both sides of the post 19, and since the only way the door can continue to close is for the links to turn over to the position shown in Figure 3, the bolt 6 must be pushed back against the spring 12 at 80 which time the roller 18 will occupy the position shown in Figure 3 and will put a heavy pressure upon the door thereby holding it tightly in its seat and preventing the loss of cold air from the refrigerator.

What I claim is as follows, but various modifications may be made in the construction shown in the drawings and above particularly described form, within the purview of my invention except as limited by the 90 claims:

1. A refrigerator door latch comprising a base plate to be attached to a door, a bolt slidable therein, a swinging lever carried by the bolt, and an abutment on the door jamb against which the swinging lever strikes and which turns said lever from a position on one side of said bolt to a position on the other side of said bolt to hold the door shut with a heavy pressure.

2. A refrigerator door latch comprising the combination with a refrigerator door of a base plate, a slidable bolt carried thereby, a fixed abutment on the door jamb, a lever pivotally mounted on the bolt to move from one side of the bolt to the other side thereof, and a roller carried by the lever to contact with the abutment of the door jamb, whereby the slidable bolt will place a heavy pressure upon the door when it is closed.

3. A refrigerator door latch comprising the combination with a refrigerator door

- jamb of a fixed abutment adapted to be secured to the door jamb, a latch plate adapted to be secured to the door, a slidable bolt in the latch plate capable of moving from one side of the bolt to the other side thereof, a spring bearing on said bolt, and a swinging lever carried by the bolt adapted to strike the fixed abutment and hold the door under a heavy pressure when closed.
- 10 4. A refrigerator door latch comprising a base plate, a slidable bolt carried thereby, a spring to hold said bolt normally in a given position, a lever carried by said bolt, capable of swinging from a position from one side of the bolt to a position on the other side of said bolt, a roller carried by said lever, and a fixed abutment member against which the swinging lever strikes to hold the door under a heavy pressure when closed.
- 10 5. A refrigerator door latch comprising a base plate fixed to a door, a slidable bolt carried thereby, a spring to hold said bolt normally in a given position, a lever adapted to swing from the end of said bolt, a latch fixture on the door jamb having a recess, pins on said fixture adapted to engage projecting hooks on said lever when closing said door whereby said lever is given approximately a half turn with its free end engaging said recess, and its pivoted end pushing back on said bolt and said spring thereby holding said door closed under pressure.
6. A refrigerator door latch comprising a base plate adapted to be fixed to a door, a slidable bolt carried thereby, a spring to hold said bolt extended, a lever secured to the end of the bolt and capable of swinging from a position from one side thereof to a position on the other side thereof, a roller carried by said lever, a pair of hooks carried by said lever and a latch fixture against which said hooks strike to turn the lever from a position on one side of said bolt to a position on the other side thereof whereby a heavy pressure may be placed upon the door to hold it closed.

In testimony whereof I have hereunto set my hand this 7th day of June A. D. 1921.

TRACY J. ANSTEY.
